CENTERING DEVICE

Joseph Kartarik, St. Paul, Minn.

Application October 27, 1939, Serial No. 301,665

2 Claims. (Cl. 77—55)

This invention relates to an improved centering device for drill bits, and the primary object of the invention is to provide a novel bit attachment adapted to accurately center a hole formed by a bit in a piece of work, relative to a countersunk opening in a member attached to the work.

A more specific object of the present invention is to provide a bit attachment of the above kind which may be readily applied to a drill bit, and which may be effectively clamped, together with the drill bit, within the chuck of a brace at a single operation.

A still further object of the present invention is to provide a centering device of the above kind which is simple in construction, durable, and efficient in use.

Other objects of the present invention will become apparent from the following description when considered in connection with the accompanying drawing, in which:

Figure 1 is an elevational view of a drill bit equipped with a centering device constructed in accordance with the present invention.

Figure 2 is a longitudinal sectional view thereof taken on line 2—2 of Figure 1.

Figure 3 is a top plan view of the same; and

Figure 4 is a transverse section on line 4—4 of Figure 1.

Referring in detail to the drawing, the present centering device comprises a tubular member through which the conventional drill D is adapted to be directed, and which is preferably composed of an upper section 5 whose lower end is in the form of an internally threaded cap 6. The remaining portion of the upper section 5 is in the nature of a reduced shank 7 rigid with and projecting upwardly from the cap portion 6 and split longitudinally at a plurality of points as at 8. The shank 7 is adapted for reception in the chuck of an ordinary brace, and by splitting the shank as at 8, said shank is capable of compression under the influence of the jaws of the brace chuck for effecting the equipped clamping action of the shank 7 upon the drill D, whereby said drill and the centering device may be locked in the chuck at a single operation.

The centering device further includes an intermediate section 9 in the form of a cylinder having an open upper end threaded into the cap portion 6 of the upper section and provided with a bottom wall having a central opening at 10. The centering device further includes a lower section 11 slidable through the bottom opening 10 of the intermediate section 9 and having an external annular flange 12 at the top thereof

arranged to abut the bottom wall of the intermediate section 9 to limit the downward movement of the lower section 11 under the influence of a helical compression spring 13 arranged in the intermediate section 9 and having its ends 5 respectively abutting the top wall of the cap portion 6 of the upper section 5 and the upper end of the lower section 11. In this way, the lower section 11 is yieldingly projected substantially flush with the lower end of the drill D, and 10 the lower end of the lower section 11 is tapered or of conical form as at 14 to provide a nose adapted to enter the countersunk opening of a member and thereby direct the drill bit D perpendicularly to this member precisely at the center of the countersunk opening. Thus, when the drill bit D is used to form an opening in the work, such opening will be accurately centered with respect to the countersunk opening of the member referred to, the lower section 11 of the 20 centering device receding as the drilling proceeds as permitted by the spring 13. The lower and intermediate sections 11 and 9 are provided in the sides with openings 15 and 16, respectively 15 to permit the escape of drilling outwardly there-through in case the same should find their way into said sections 11 and 9 of the device.

The present invention will be found of great value when it is desired to fasten a metal plate onto a backing by screws, which plate is drilled 30 and provided with proper countersinks for the screw heads. In order that the screws shall have their heads rest flush with the surface of the plate when they are screwed home, it is necessary that the screws be started exactly in the 35 center of the countersunk hole, as well as accurately perpendicularly to the plate. Otherwise, the head or one side thereof would project above the plate. By means of the present attachment, this true centering can be readily and accurately 40 performed without depending upon the skill and judgment of the mechanic. The device is extremely simple, convenient to use, and efficient. While I have shown what I believe to be a preferred embodiment of the present invention, it 45 will be understood that the same is capable of various modifications and changes in specific details of construction.

While the main purpose of the present invention is to center a drill bit as above described, it will be noted that the device acts as a guide which braces the drill bit against deflection and breakage. Also, by varying the position of the drill bit longitudinally with respect to the de- 50 55

vice, the latter will act to regulate the depth of drilling.

What I claim as new is:

1. A centering device for drill bits comprising
5 a tubular member through which the drill bit is
adapted to be directed, said tubular member
comprising an upper section reduced at its upper
end to provide a shank, and a spring projected
lower section having a conical lower end pro-
10 viding a nose adapted to enter a countersunk
opening with which an opening to be formed by
the drill is adapted to be centered, said shank
being split longitudinally so as to be capable of
compression whereby the centering device and
15 drill may be secured in a chuck at a single opera-
tion, said upper section consisting of an inter-
nally threaded cap having the shank rigid
with and projecting upwardly therefrom, and a
cylindrical intermediate section threaded into
20 said cap at its upper end and having a central
opening in the bottom thereof through which the
lower section slidably projects, said lower section
having an external annular flange on the upper
end thereof arranged to abut the bottom of the
25 intermediate section to limit the projection of
said lower section, and a helical compression
spring arranged in the intermediate section and
having its ends respectively bearing against said
cap portion and the top of said lower section.

2. A centering device for drill bits comprising
a tubular member through which the drill bit is
adapted to be directed, said tubular member
comprising an upper section reduced at its upper
end to provide a shank, a spring projected lower
5 section having a conical lower end providing a
nose adapted to enter a countersunk opening
with which an opening to be formed by the drill
is adapted to be centered, said shank being split
longitudinally so as to be capable of compression
10 whereby the centering device and drill may be
secured in a chuck at a single operation, said
upper section consisting of an internally thread-
ed cap having the shank rigid with and project-
ing upwardly therefrom, a cylindrical interme-
15 diate section threaded into said cap at its upper
end and having a central opening in the bottom
thereof through which the lower section slidably
projects, said lower section having an external
annular flange on the upper end thereof ar-
20 ranged to abut the bottom of the intermediate
section to limit the projection of said lower sec-
tion, and a helical compression spring arranged
in the intermediate section and having its ends
respectively bearing against said cap portion and
25 the top of said lower section, said lower and in-
termediate sections having openings through the
sides thereof for the escape of drilling.

JOSEPH KARTARIK.
